(57) **CLAIM**

The ornamental design for socket for wrench, as shown and described.

DESCRIPTION

FIG. 1 is a front view of a socket for wrench showing our new design, wherein the rear view is a mirror image thereof. FIG. 2 is a left side view of the socket for wrench of FIG. 1.

FIG. 3 is a right side view of the socket for wrench of FIG. 1.

FIG. 4 is a top view of the socket for wrench of FIG. 1, wherein the bottom view is a mirror image thereof.

FIG. 5 is a perspective view of the socket for wrench of FIG. 1;

FIG. 6 is a section view of the socket for wrench of FIG. 1 taken along line VI-VI of FIG. 1; and,

FIG. 7 is a section view of the socket for wrench of FIG. 1 taken along line VII-VII of FIG. 2.

1 Claim, 4 Drawing Sheets
